UNITED STATES PATENT OFFICE.

FREDERICK A. WAGNER, OF ROCHESTER, NEW YORK, ASSIGNOR TO FREDERICK A. WAGNER CO. INC., OF ROCHESTER, NEW YORK, A CORPORATION OF NEW YORK.

PUMP.

Application filed May 1, 1923. Serial No. 635,958.

To all whom it may concern:

Be it known that I, FREDERICK A. WAGNER, a citizen of the United States, residing at Rochester, in the county of Monroe and 5 State of New York, have invented certain new and useful Improvements in Pumps; and I do hereby declare the following to be a full, clear, and exact description of the same, reference being had to the accompanying drawings, forming a part of this specification, and to the reference numerals marked thereon.

My present invention relates to pumping apparatus and more particularly to equipment designed for household use to provide a constant supply of running water from an individual tank and an automatically operated power unit connected therewith and the invention has for its object to provide 15 an improved apparatus of this character that will be compactly arranged and easily shipped and set up or dismounted by relatively unskilled persons. The improvements are further directed toward providing a 20 positively acting mechanism so protected and arranged as to give long service with very little attention. To these and other ends the invention resides in certain improvements and combinations of parts all 25 as will be hereinafter more fully described, the novel features being pointed out in the 30 claims at the end of the specification.

In the drawings:

Figure 1 is a front view of a pumping 35 unit constructed in accordance with and illustrating one embodiment of my invention;

Figure 2 is a top view thereof;

Figure 3 is a detail sectional view of the 40 tank connection taken on the line 3—3 of Figure 1;

Figure 4 is a vertical section, slightly enlarged, taken longitudinally through the pumping cylinder on the line 4—4 of Figure 2 and

Figure 5 is an enlarged transverse section 45 through the pumping cylinder and valves on the line 5—5 of Figure 2.

Similar reference numerals throughout the several views indicate the same parts.

Referring more particularly to the drawings 50 1 indicates the usual type of vertical pressure tank having an intake 2 and discharging at 3, the tank resting preferably directly on the floor. Adjacent to the tank 55 and having a reentrant curved portion 4 fit-

ting against the side thereof is a table 5 upon which the entire pumping mechanism is mounted. The table is supported at three points by front legs 6 and a rear leg 7 paralleling the tank which insures its stability. 60 It is held securely to the tank at the top or in its own plane by a strap 8 embracing the tank and secured in lugs 9, projecting laterally from the table, by nuts 10. A similar strap or band 11 lower down has its ends 65 secured by nuts 12 in lugs 13 on the rear most leg 7. The unit is shipped completely assembled except for the attachment of the table to the tank and the necessary pipe connections hereinafter described. All the pur- 70 chaser has to do is to make these pipe connections and apply the straps 8 and 11 with the four nuts which is a simple matter.

The table is preferably substantially 75 square as shown. Extending from side to side at the front thereof is the pump embodying a cylinder and valve case 14 and a crank case 15 folded together at 16. The pump cylinder 17 contains a piston 18 on a piston rod 19 acting through a stuffing box 80 20 located at the joint between the two cases. At the opposite end of the piston rod is a cylindrical cross head 21 having a suitable guideway 22 in the extension of the crank case to which cross head the crank 23 85 is connected by a wrist pin 24. The crank, counterweighted at 25, has a bearing 26 on the crank 27 of a crank shaft 28 extending transversely through the crank case 15. Fixed to this shaft is a gear 29 meshing 90 with a pinion 30 on a drive shaft 31 aligned and having a direct connection with the shaft 32 of a suitable electric motor 33 constituting the source of power and preferably driving through a flexible coupling 34 joining it to the shaft 31. 95

The pump is double acting, one end communicating with a water chamber 35 and the other with a water chamber 36 in the case 14. These chambers are supplied with 100 water from a common supply chamber 37 arranged at the lower front portion of the case 14 and into which leads the supply pipe 38 connected to the source of water supply. Communication from the supply chamber 37 to the respective chambers 35 and 36 is had through intake valves 39 one of which is shown in Figure 5. Each valve consists of a cage 40 forming the seat and having a central lug 41 supporting a post 42 in the pres- 110

ent form of a shouldered screw having a head 43. The valve 39 is a disc valve movable on the post and closed by a spring 44 surrounding the latter. Upward movement 5 of the valve against the tension of the spring is limited by the head 43. The spring at its upper end bears against a plug 45 which is removable and of such a size as to then give access to the entire valve and 10 permit the removal of the cage 40 if required. This is of great convenience in cleaning and adjusting the valves.

Opposite each intake valve 39 and at an elevation above the same to the rear of and 15 above the cylinder 17 is a discharge valve 46 constructed and operating the same as the intake valves 39 and similarly accessible through the removal of plugs 47. They lead from the respective chambers 35 and 36 20 to a discharge chamber 48 from which runs a pipe line indicated generally at 49 delivering into the tank 1 at 2. The operation of the pump and valves will be obvious to one skilled in the art—when the piston 25 18 moves to the left in Figure 4 the intake valve 39 is raised in chamber 36 and the discharge valve opens in chamber 35 while on the reverse stroke there is a similar result with respect to the other two valves. It is 30 to be noted in this connection that the discharge valves 46 are at the tops of the L-shaped chambers 35 and 36 while the intake valves 39 are at the low level of these chambers with the result that if air enters with 35 the water it will collect in the vicinity of the discharge valve and easily escape therethrough and not interfere with the operation of the intake valve.

The cylinder 17 and piston 18 are also 40 made accessible through an aligned plug 50 of the nature of the plugs 45 and 47 for the valves and this plug is provided with a petcock 51 leading into the chamber 36. Sometimes the air becomes so depleted in 45 the tank 1 that it is desirable to pump in more air along with the water without emptying the tank and it is for this purpose that the petcock is provided.

The usual form of air chest 52 is provided 50 on the discharge chamber 48 to maintain a uniform pressure in the line 49. There is also located in said line a suitable pressure valve 53 which may be adjusted to yield at a given overload and discharge the 55 water at 54 if for any reason the pump continues after the tank has been filled.

In the usual operation of the system and as before stated, the water enters the tank at 2 and discharges at 3 through the service 60 pipe 55 provided with a suitable pressure gage 56. Such water is stored for a time within the tank and it is sometimes desired to obtain a direct supply of freshly pumped water as for instance when the water is 65 drawn from a well and it is desired to have

cold water for drinking purposes. For this purpose I provide a fresh water line 57 leading from the line 49 which latter is provided at the coupling with a suitable three-way valve the stem of which is indicated at 58. Through the operation of this valve the water delivered by the pump instead of going to the tank can be diverted through the line 57.

The intake or supply pipe 38 is provided 75 with a priming chest 59 closed at the top by a plug 60. Also, by removing this plug air may be pumped into the tank for brief intervals which is necessary at times in order to maintain in the tank a sufficient 80 body of air to maintain pressure.

The motor 33 is controlled by a suitable pressure switch so that it is automatically called into use when the pressure in the supply line 49 falls below a predetermined 85 point. This switch is located in the case 61 extending from a case 62 in which the diaphragm is housed. The circuit wires to the motor are indicated at 63 and the pressure line to the diaphragm from the pump line 90 49 is indicated at 64 but as pressure switches of this nature are generally known and such device in its details forms no part of the present invention, its interior arrangements 95 are not shown.

It will be seen from the foregoing that my apparatus is compact and easily set up. The motor, pump, valve case and in fact all of the devices arranged on the table 5 are 100 simple in construction and so arranged as to be readily accessible at all times. It is to be noted that the direct drive from the motor 33 to the pump crank shaft does away with the belts usually employed in apparatus 105 of this kind and which are a common source of trouble particularly where, as is often the case, the apparatus is located in a cellar where the air is damp or foul.

I claim as my invention:

1. In a pumping apparatus, the combination with an upright cylindrical tank, of a table having legs supporting it adjacent to the tank, one of said legs being against the latter, a pair of bands embracing the tank, the ends of one band being detachably connected to the table and the ends of the other band being detachably secured to the said leg, a pump supported on the table and a pipe line therefrom detachably connected to the tank.

2. In a pumping apparatus, the combination with a tank and a table having one side secured to the tank and the opposite side provided with depending supporting means, of a pump upon the table connected with the tank and embodying a crank shaft and a cylinder having a piston operatively connected with the crank shaft, and a motor upon the table having a shaft aligned with and connected to the crank shaft.

3. In a pumping apparatus, the combination with a vertically disposed tank, of a table having one side engaging the tank and the opposite side provided with depending legs, means for clamping the first mentioned side of the table upon the tank, and a pump supported upon the table and having a connection leading to the tank.

4. In a pumping apparatus, the combination with a vertically disposed tank, of a table having spaced lugs at one side thereof disposed upon the tank and depending supporting means at the other side of the table, means adapted to clamp the lugs upon the tank, and a pump supported by the table and having a supply pipe leading to the tank.

5. In a pumping apparatus, the combination with a vertically disposed tank, of a table having one side thereof disposed ad-

jacent the tank and provided with depending supporting means, a band embracing the tank and having its opposite ends secured to the table to clamp the latter upon the tank, means adapted to connect said depending supporting means with the tank in a plane below the top of the table, and a pump upon the table having a supply connection leading to the tank.

6. In a pumping apparatus, the combination with a vertically disposed tank, of a table having lugs at one side thereof disposed in engagement with the tank, depending supporting means for the table, means for clamping the lugs upon the tank, independent means for connecting said supporting means with the tank, and a pump upon the table having a supply connection leading to the tank.

FREDERICK A. WAGNER.
